UNITED STATES PATENT OFFICE

2,333,860

CIRCULAR PRESS

David Gup, Rochester, N. Y., assignor to The West Tire Setter Company, Rochester, N. Y., a corporation of New York

Application December 12, 1942, Serial No. 468,775

9 Claims. (Cl. 153—1)

This invention relates to a circular press, with more particular reference to the type of apparatus employing a series of radially movable dies operating simultaneously to engage a work piece, and it has for its purpose to provide such a machine with a practical, simple, and efficient mechanism operable to crimp or indent a metal cap or other outer member at several circumferentially spaced points into correspondingly spaced recesses or pockets formed in the outer surface of an inner cylindrical member such as a shell, projectile, or the like to which the outer member is to be attached.

More particularly the invention has for an object to provide a circular press with a die having a concave operative surface engaging a portion of the surface of the work piece and a convex operative surface adjacent thereto and extending inwardly beyond said concave surface and operating to crimp or indent a portion of the cap or outer member into a recess of the inner member for attachment thereto.

A further purpose of the invention is to provide such a die in two parts, the portion which performs the crimping operation comprising a circular member having an operative surface that is convex in perpendicular planes, said member being adjustably secured to the body portion of the die so as to permit using every portion of its periphery as it becomes worn at one part thereof.

Another object of the invention is to afford an efficient form of crimping means for the purpose outlined, comprising a circular member having a transversely convex peripheral operative surface, and adjustably mounted to permit the use of different portions of its operative surface, or the crimping member may be fixed and provided with an operative surface that is convexly curved in perpendicular planes.

Still an additional object of the invention is to afford simple and efficient means for guiding the die accurately to operative position by the instrumentality that attaches the crimping member to the die, and also structure for automatically seating the cap or outer member in proper position in relation to the dies, so that the cap is correctly and accurately related to the shell or inner member to which it is to be attached by the crimping operation.

To these and other ends, the invention consists in the construction and arrangement of parts that will appear clearly from the following description when read in conjunction with the accompanying drawings, the novel features being

pointed out in the claims following the specification.

In the drawings:

Fig. 1 is a plan view showing the general arrangement of a circular press incorporating a preferred embodiment of the present invention;

Fig. 2 is a vertical central sectional view, partially broken away, showing the construction of the work support and dies, and with a work piece in operative position;

Fig. 3 is a plan view of the work support with the dies and other mechanism removed;

Fig. 4 is an end view of one of the dies and the crimping member in position; and

Fig. 5 is a plan view of the die with the crimping member removed.

The invention is designed for use in conjunction with a hydraulic circular press such as disclosed in Patent No. 2,256,740, September 23, 1941, and it will be unnecessary in connection with the disclosure of the present invention to enter into detail as to the operating and controlling mechanism for radially moving the rams on which the dies are mounted, as it will be understood that this structure is similar to that of the aforementioned patent.

Referring more particularly to the drawings in which like reference numerals refer to the same parts throughout the several views, 1 designates each of the several carriers movable back and forth on a table 2 and provided with a cylinder 3 cooperating with a stationary piston 4 and actuated inwardly when pressure fluid is permitted to flow into the cylinder through the pipe 5, the carriers being returned to their outer or normal positions by the springs 6.

Each carrier 1 has a die mounted thereon and each of said dies includes an attaching portion 7 having a curved rear edge 8 fitting against a correspondingly curved surface on the carrier 1, the die being held in place by a bolt 9 as in the structure of the aforementioned patent. Inwardly of the attaching portion 7, the die includes a body portion 10 that terminates in a concave operative surface 11, and is cut away at its upper portion to afford a dished seat 12 which terminates at its rear edge in an arc-shaped back wall 13 having a curvature corresponding to that of the crimping member now to be described.

Since there is greater wear and strain on the crimping or indenting portion of the die than on the rest of its operative surface, it is desirable to provide a crimping member that is adjustable so as to utilize fresh portions when one part becomes excessively worn, and to accomplish this

there is employed a circular crimping member as shown at 14, having an opening to receive a bolt 15, that extends through a similar opening in the body portion of the die and is held in place by means of the nut 16 so as to securely and rigidly attach the circular crimping member 14 to the die.

The circular crimping member 14 has a transversely convex periphery extending beyond the concave operative surface 11 of the body portion of the die, as shown in Fig. 2, thus affording an operative surface that is convex in perpendicular planes and is held in place with its circumferentially and transversely curved periphery fitting against the correspondingly arc-shaped back wall 13 of the die which thus affords a rigid support for the crimping member against lateral pressure.

After a crimping member has been used repeatedly and the operating portion of its surface excessively worn, it can be turned on its seat by loosening the nut 16, to bring a fresh portion of its periphery into operative position, without affecting the rigidity of its attachment to the body portion of the die or the efficiency of its operation. In this fashion, the crimping member can be used by repeated adjustments on the die, until every portion of its periphery has been utilized, although it is to be understood that the crimping operation could be successfully performed by an integral die in which the convex crimping portion and the body portion of the die with a concave operative surface are formed in one piece.

In the construction shown, the machine is arranged to fasten a conventional cap A on to a shell or projectile B, the latter being provided for the purpose with suitable indentations or recesses C at spaced intervals around its periphery, and it is desirable to position the cap A in such relation to the crimping members that the latter will engage the edge of the cap and force portions of the edge into the indentations.

The edge of the cap preferably occupies a position slightly beneath the upper surface of the crimping members and adjacent to the horizontal axis of the latter, the cap being positioned in a work support that maintains the cap in proper relation to the crimping member.

The work support is designated at 18 and includes a central opening 19 somewhat larger than the head of the cap, while 21 designates a shoulder at the top of the opening 19 and arranged to support the body portion of the cap which rests on the shoulder 21 when in operative position. The work support 18 is suitably attached by bolts to a base 22 which has a central opening 23 to receive the tip of the cap and is suitably mounted on a stationary part of the machine designated at 24.

In operation, the cap A is first inserted into the work support inverted as shown until it rests upon the shoulder 21 and the shell B is then inserted within the cap, the operator positioning the shell so that the recesses or indentations C are in vertical alignment with the operative portions of the crimping members, the shell being lowered as far as it will go and limited in its downward positioning movement by the inner diameter of the cap.

The machine is then operated to cause inward radial movement of the several carriers, moving the crimping members inwardly so that they force the adjacent portions of the edge of the cap into the recesses on the shell while the concave surfaces of the dies below the crimping members engage the outer periphery of the cap

below its edge portion and properly center the cap while preventing any distortion thereof which might otherwise occur.

It is essential to the efficient and correct operation that the dies be guided accurately in their radial movement so that the operative surfaces of the crimping members will be in correct vertical alignment with the recesses in the inner member, and in order to accomplish this, means are provided for controlling and guiding the movement of the dies at points in close proximity to their operative portions.

This is preferably brought about by providing the work support 18 with a series of radially disposed slots 26 extending from the outer edge of the work support inwardly and cooperating with the heads 27 on the bolts 15 aforementioned. Each slot 26 is of such size as to afford a reasonably close fit with its head 27 and also permit radial movement of the latter as the die moves inwardly, while at the same time insuring an accurate straight line movement of the operative surfaces of the die as it engages the work piece.

While the invention has been shown as embodied in a machine including six carriers and dies, it may also be applied to a machine utilizing any number of radially movable carriers and dies disposed symmetrically around the work piece, or to a single carrier and die.

The structure shown can be manufactured at a minimum cost and readily assembled. The crimping members can be quickly adjusted to different positions without affecting their accurate operation and efficiency until every portion of their peripheral surfaces have been utilized and can be quickly replaced when necessary.

While the invention has been shown in connection with the mechanism illustrated, it is not confined to this precise embodiment, and this application is intended to cover such modifications and departures as may come within the purposes of the improvements and the scope of the following claims.

I claim:

1. In a circular press including a series of radially movable carriers and fluid means for simultaneously actuating the carriers inwardly, a die mounted on each carrier and including a concave operative surface and a seat defined by an arc-shaped back wall, and a circular crimping member secured to said seat and rotatably adjustable thereon, said circular crimping member having a transversely convex peripheral operative surface a part of which engages said arc-shaped back wall and a portion of which extends beyond said concave operative surface and acts to crimp a portion of an outer cylindrical member into a recess of an inner cylindrical member to which it is to be attached.

2. In a circular press including a series of radially movable carriers and fluid means for simultaneously actuating the carriers inwardly, a die mounted on each carrier and including a concave operative surface and a seat defined by an arc-shaped back wall, a circular crimping member secured to said seat and rotatably adjustable thereon, said crimping member having a transversely convex peripheral operative surface a part of which engages said arc-shaped back wall and a portion of which extends beyond said concave operative surface and acts to crimp a portion of an outer cylindrical member into a recess of an inner cylindrical member to which it is to be attached, the die having a vertical opening therethrough, a bolt extending through said opening

for fastening the crimping member in place, said bolt having a head projecting below the die, and a stationary work support having a radial slot in which said bolt-head and the die are guided.

3. In a circular press for crimping a band on a cylindrical body including a series of radially movable carriers and fluid means for simultaneously actuating the carriers inwardly, a die mounted on each carrier and including a concave operative surface conforming to and engageable with the exterior surface of the band, said concave operative surfaces of the dies engaging the band entirely therearound, a seat on the die, and a circular crimping member secured to said seat and rotatably adjustable thereon, said circular crimping member having a transversely convex peripheral operative surface located in a plane spaced from said concave operative surface and having a portion which extends beyond said concave operative surface and acts to crimp a portion of an outer cylindrical member into a recess of an inner cylindrical member to which it is to be attached.

4. In a circular press for crimping a band on a cylindrical body including a series of radially movable carriers and fluid means for simultaneously actuating the carriers inwardly, a die mounted on each carrier and including a concave operative surface conforming to and engageable with the exterior surface of the band, said concave operative surfaces of the dies engaging the band entirely therearound, a seat on the die, and a circular crimping member secured to said seat and rotatably adjustable thereon, said circular crimping member having an operative surface located in a plane spaced from said concave operative surface and having a portion which extends beyond said concave operative surface and acts to crimp a portion of an outer cylindrical member into a recess of an inner cylindrical member to which it is to be attached.

5. In a circular press for crimping a band on a cylindrical body including a series of radially movable carriers and fluid means for simultaneously actuating the carriers inwardly, a die mounted on each carrier and including a concave operative surface conforming to and engageable with the exterior surface of the band, said concave operative surfaces of the dies engaging the band entirely therearound, and adjacent to the concave operative surface a second operative surface that is convexly curved away from the band, said second operative surface acting to crimp a portion of an exterior cylindrical member into a recess of an interior cylindrical member to which it is to be attached.

6. In a circular press including a series of radially movable carriers and fluid means for si-

multaneously actuating the carriers inwardly, a die mounted on each carrier and including a concave operative surface and a seat defined by an arc-shaped back wall, a circular crimping member secured to said seat and rotatably adjustable thereon, said crimping member having a transversely convex peripheral operative surface a part of which engages said arc-shaped back wall and a portion of which extends beyond said concave operative surface and acts to crimp a portion of an outer cylindrical member into a recess of an inner cylindrical member to which it is to be attached, the die having a vertical opening therethrough, a bolt extending through said opening for fastening the crimping member in place, said bolt having a head projecting below the die, and a stationary work support having a radial slot in which said bolt-head and the die are guided, said work support having a central opening to receive the end of the exterior cylindrical member and a shoulder surrounding the upper end of said opening for supporting said member.

7. In a circular press including a series of radially movable carriers and fluid means for simultaneously actuating the carriers inwardly, a die mounted on each carrier and including a seat defined by an arc-shaped back wall, and a circular crimping member secured to said seat against the back wall and rotatably adjustable thereon.

8. In a circular press including a series of radially movable carriers and fluid means for simultaneously actuating the carriers inwardly, a die mounted on each carrier and including a seat defined by an arc-shaped back wall, a circular crimping member arranged on said seat against the back wall, the die having a vertical opening therethrough, a bolt extending through said opening for fastening the crimping member in place, said bolt having a head projecting below the die, and a stationary work support having a radial slot in which said bolt-head and the die are guided.

9. In a circular press including a series of radially movable carriers and fluid means for simultaneously actuating the carriers inwardly, a die mounted on each carrier and including a seat defined by an arc-shaped back wall, a circular crimping member arranged on said seat against the back wall, said crimping member having a transversely convex peripheral operative surface, the die having a vertical opening therethrough, a bolt extending through said opening for fastening the crimping member in place, said bolt having a head projecting below the die, and a stationary work support having a radial slot in which said bolt-head and the die are guided.

DAVID GUP.
